UNITED STATES PATENT OFFICE

ALEX LAIST, OF HELENA, MONTANA, ASSIGNOR TO ANACONDA COPPER MINING COMPANY, A CORPORATION OF MONTANA

TUYÈRE FOR SLAG-BLOWING FURNACES

Application filed August 4, 1928. Serial No. 297,451.

In tuyères for slag-blowing furnaces and similar apparatus, a stream of air is caused to flow in a horizontal direction immediately at or prior to, its passage through the tuyère and a downwardly flowing stream of pulverized fuel, suspended in air, is caused to enter the air stream at an angle. In tuyères heretofore used, the impinging of the stream of powdered coal on the air stream deflected the resultant stream downwardly from the horizontal, and thus caused the mixed stream and the particles of suspended fuel to strike the wall of the tuyère. The striking of the suspended particles on the wall of the tuyère caused a rapid erosion or wearing away of the tuyère and, therefore, necessitated frequent repairs or replacement.

This advantage is obviated in my present invention which provides a tuyère and an air and fuel supply means that avoids any impingement of fuel, or other particles, on the wall of the tuyère and thus preserves the tuyère against erosion, and that enables the mixed air and fuel stream to flow substantially horizontally or parallel to the tuyère passages.

The various features of the invention are illustrated in the accompanying drawings, in which:

Fig. 1 is a plan view of a tuyère embodying a preferred form of the invention.

Fig. 2 is a vertical sectional view of the tuyère taken on the line 2—2 of Fig. 1.

Fig. 3 is a vertical section taken on the line 3—3 of Fig. 2, and

Fig. 4 is an end view of the tuyère.

In the type of tuyère to which my present invention is applied air under pressure is supplied downwardly through a vertical pipe 10 to a casting 11 into which the pipe is threaded. The air is received in a chamber 12 which is formed in the outer end of the casting and is closed by an end plate 13. From the chamber 12 the air flows through a passageway 14 into a mixing chamber 15 of a somewhat rounded or globular shape. In the chamber 15 the air is joined by a stream of fuel suspended in air and then passes through an outlet passage 16 into a tuyère

pipe 17 that leads through the wall of the converter or furnace.

A stream of powdered fuel suspended in a carrying current of air, under pressure, is supplied downwardly through a pipe 18 positioned between the air pipe 10 and the wall 19 of the converter. From the pipe 18 the air is received in an expansion chamber 20 formed in the casting 11 immediately above and opening downwardly into the mixing chamber 15. The expansion chamber 20 is of considerably larger horizontal cross section than is the fuel admission pipe 18 and also increases in cross sectional area downwardly towards the mixing chamber 15. It is preferably of rectangular cross section having parallel walls 21 and 22 at right angles to the horizontal direction of flow of the air through the mixing chamber 15, and having a pair of diverging walls 23 and 24 that meet the outermost part of the mixing chamber 15 at approximately a tangent thereto. Immediately upon entering the expansion chamber 20, the cross-sectional area of the passage for the air and its suspended fuel is increased and the velocity is correspondingly reduced. As the air and fuel pass downwardly through the chamber 20, the cross-sectional area widens to the diameter of the chamber 15 and the air and suspended fuel, therefore, enter the mixing chamber 15 uniformly distributed across the path of the air passing horizontally therethrough, and at a velocity insufficient to materially deflect the stream of air. The particles of suspended fuel are, therefore, carried horizontally by the passing air without impinging, to any destructive extent, upon the side walls of the tuyère.

The tuyère may be provided with the usual slag overflow pipe 25 secured in an opening at the lower part of the chamber 15 and sealed therefrom by means of a fusible disc 26 held in place by a bushing 27. The end plate 13 may also be provided with an inlet check valve 28 of usual construction.

As changes of construction could be made within the scope of my invention, it is intended that all matter contained in the above description or shown in the accompanying

drawings shall be interpreted as illustrative and not in a limiting sense.

In previous applications of Garred No. 181,979 filed April 8, 1927, and of myself No. 284,462 filed June 11, 1928, there are described apparatus for recovering zinc and other metals from slags or the like, by blowing through the molten material a mixture of air and finely divided coal or other fuel.

10 The present improvement is designed particularly for use in such blowing operations, though it may be used with advantage wherever similar conditions exist.

Having now described my invention, what 15 I claim as new and desire to secure by Letters Patent is:

1. A tuyère of the type described which comprises a horizontal air passage, and a fuel passage entering said air passage at 20 an angle, said fuel passage being enlarged adjacent its entrance to said air passage to reduce the velocity of fuel prior to its entrance to said air passage.
2. A tuyère of the type described which 25 comprises a horizontal air passage, and a fuel passage entering said air passage at a right angle, said fuel passage being enlarged adjacent its entrance to said air passage to reduce the velocity of fuel passing there- 30 through prior to its entrance to said air passage.
3. A tuyère of the type described which 35 comprises an air passage, a fuel passage opening into said air passage at an angle, the cross sectional area of said fuel passage increasing towards said air passage.
4. A tuyère of the type described which 40 comprises a casting having an air passage therethrough, a fuel passage opening at right angles to said air passage and having parallel front and back walls at a right angle to the direction of flow through said air passage, and side walls diverging towards said air passage.

45 In witness whereof, I have hereunto signed my name.

ALEX LAIST.
